John Winston Attorney

UNITED STATES PATENT OFFICE.

SIMON KLOTZ, OF BIRMINGHAM, ALABAMA, AND SIMON LAZARUS, OF LOUISVILLE, KENTUCKY.

SAFETY-ENVELOP.

1,307,447.

Specification of Letters Patent. Patented June 24, 1919.

Application filed August 26, 1918. Serial No. 251,373.

To all whom it may concern:

Be it known that we, SIMON KLOTZ and SIMON LAZARUS, citizens of the United States of America, residing at Birmingham and Louisville, respectively, in the county of Jefferson and States of Alabama and Kentucky, have invented certain new and useful Improvements in Safety-Envelops, of which the following is a specification.

10 This invention relates to a safety fastening for envelopes which is intended not only to make surer and more positive the closing of the envelop but also to design the fastening for the flap of such character that the latter can be easily opened but not without defacing the envelop in such manner as to indicate that it has been tampered with.

15 The principal object of our invention is to make use of a metallic fastener attached to the back of the envelop and provided with prongs or tips adapted to perforate and be folded down upon the back flap so as to secure the latter while the flap is provided with a gummed portion which can be folded 20 and secured over the bent prongs so as to conceal them and prevent them being tampered with.

It is a further object of our invention that the fastening be so arranged as to facilitate the opening of the envelop and to this end the sides of the flap are preferably left unglued while the center or tip of the flap is gummed on its outer surface only so that this gummed tip may be folded back over 30 and form the protection for the metallic fastener. This arrangement enables one to readily grasp the back flap and tear it open without requiring the cutting or slitting of the envelop.

40 These and other advantages of our invention will be better understood by reference to the accompanying drawings which illustrate our invention only in its preferred embodiment, and in which:—

45 Figure 1 shows the back of the envelop with the flap raised to disclose the metallic fastener.

Fig. 2 shows the flap fastened by the metallic fastening; and

50 Fig. 3 shows the gummed flap protecting the metallic fasteners.

Similar reference numerals refer to similar parts throughout the drawings.

Our invention is applicable to any standard type of envelop such as is formally designated by the numeral 1 in the drawings, it being understood that our invention is not concerned in the shape, size, or material of the envelop. The back 2 of the envelop is provided with any suitable type of flat metallic fastener 3 which is secured thereto in any suitable manner in position to underlie the back flap 4 when the latter is in closed position. The metallic fastener 2 is provided with tips or points 5 which are adapted to 60 be bent up into position to perforate the flap and be bent down thereover to secure the flap in its closed position, as shown in Fig. 2. The fastener is disposed at such distance from the tip or bottom edge of the back flap 70 4 that the latter can be folded back over the exposed tips 5 of the metallic fastening to conceal the latter. This concealing or protecting tip of the back flap I have designated as 6 and the outer surface of this tip is gummed 75 at 7, or the gum is so applied to the envelop as to secure this tip of the back flap over the metallic fastening to conceal the latter.

The normal provision of gum along the 80 inside edges of the back flap 4 may be dispensed with if desired or may be retained, such being immaterial for the purposes of this invention. Preferably the lower tip 6 of the normal style back flap is employed as the medium for concealing the metallic fastening, but where desired the back flap of the envelop may be especially designed with our ends in view or may be provided with supplemental or ornamental flaps 6 as conditions may justify.

90 This invention is not intended to be restricted in scope to the specific embodiments shown, but contemplates such modifications as come within the spirit and scope of the claims.

Having thus described our invention, what we claim as new and desire to secure by Letters Patent, is:—

1. An envelop comprising a front and a back body portion, and a back flap adapted 100 to fold down over the back body portion and having its tip gummed only on its outer

surface, and a metallic fastener carried by the back body portion with its prongs outwardly and disposed to penetrate the flap immediately above said gummed tip and in position to be concealed by the latter when folded back upon and sealed to the outer surface of the flap.

2. An envelop having a back body portion carrying at the center of its top a metallic fastener, the prongs of which pierce and project outwardly through said body portion, and a triangular shaped back flap, the free tip of which is left ungummed on its under surface, said metallic fastener being

disposed for its prongs to pierce the flap adjacent to said ungummed tip and in position to be concealed by said tip when folded outwardly back upon itself, and adhesive means to seal said tip in position to conceal the prongs of the metallic fastener, substantially as described.

In testimony whereof we affix our signatures.

SIMON KLOTZ.
SIMON LAZARUS.
